UNITED STATES PATENT OFFICE.

FRANK E. CROTTO, OF DALLAS, TEXAS.

WELL-WASHING DEVICE.

Application filed April 25, 1921. Serial No. 464,285.

To all whom it may concern:

Be it known that I, FRANK E. CROTTO, a citizen of the United States, residing at Dallas, in the county of Dallas and State of Texas, have invented certain new and useful Improvements in Well-Washing Devices, of which the following is a specification.

This invention relates to new and useful improvements in well washing devices.

10 The object of the invention is to provide a washing device for artesian wells without screens and in which an enlarged pocket is formed at the bottom of the well. A particular feature of the invention is the provision of outwardly swinging nozzles arranged to be swung outwardly by the pressure of the washing fluid and automatically retracted when the pressure is cut off. Another object is to provide a plurality of nozzles, whereby the washing is carried out more expeditiously and more evenly performed.

20 A particular feature of the invention is to individually mount the nozzle, whereby the obstruction to one or more will not prevent 25 the outward displacement of the other. Another result sought is to make the device in a compact and simple manner and in this respect is an improvement on my application filed January 31, 1921, Serial No. 30 441,257.

A construction designed to carry out the invention will be hereinafter described together with other features of the invention.

The invention will be more readily understood from a reading of the following specification and by reference to the accompanying drawings, in which an example of the invention is shown and wherein:

Fig. 1 is an elevation of a device constructed in accordance with my invention, the nozzles being extended in the well,

Fig. 2 is a vertical sectional view, indicating the extended position of the nozzles in dotted line,

Fig. 3 is a cross sectional view on the line 3-3 of Fig. 2,

Fig. 4 is a cross sectional view on the line 4-4 of Fig. 2, and

Fig. 5 is a cross sectional detail on the line 5-5 of Fig. 2.

In the drawings the numeral 10 designates a cylindrical housing having a solid core 12 in its lower portion and terminating flush with its lower end which receives a 55 guide plug 11. Immediately above the core the housing is provided with an inwardly

extending annular bead 13 on which a socket plate 14 is supported. The plate 14 has a plurality of equally spaced sockets 15 suitably shaped to receive the ball heads 16 of 60 nozzles 17 depending from said plate. The nozzles have their lower ends curved outwardly and beveled, whereby the bore of the nozzle is directed outwardly. Each nozzle is received in a socket 18 formed in the side 65 of the housing and the core 12.

The nozzles are held normally in their sockets. A keeper plate 19 is notched out to fit over the heads 16 and prevents the displacement of the same from the sockets 15. 70 Each head 16 has a pair of ears 20 between which the lower end of an angular plunger 21 is pivoted. The plunger extends up through fingers 22 extending from the lower edge of an inverted valve cap 23. The 75 plungers are angular in cross section so as to slide vertically between the fingers and whereby rotation is obviated. Each plunger has its portion normally extending above the fingers, substantially perpendicular and 80 below said fingers is inclined inwardly to its point of engagement with the ears 20. Coiled springs 24 are confined on the lower portions of the plungers between the fingers and collars 25; while other coiled springs 26 85 are confined on the upper portions of the plungers between the fingers and collars 27. The coiled springs 26 have a greater tension than the coiled springs 24 whereby the plungers are held elevated and the nozzles 90 17 are retained in their sockets.

An enlarged collar 28 has its lower end reduced and screw threaded into the upper end of the housing 10 whereby a flush exterior joint is had. The upper end of the 95 collar is contracted into a nipple 29 and receives the lower end of a string of pipe 30. A bushing 31 is screwed into the nipple from the interior of the collar and telescoped into the cap 23. The cap 23 is provided with a 100 transverse pin 32 passing through slots 33 in the lower end of said bushing. A coiled spring 34 has its lower end fastened on the pin 32 and its upper end supported on a transverse pin 35 mounted in the upper end 105 of the bushing. The bushing is provided with a plurality of ports 36 which are normally covered by the cap 23. The cap 23 in connection with the bushing constitutes a valve which is normally closed.

In operation the device is lowered into the well until the housing 10 is within the

oil sand pocket or other cavity. The cleaning fluid, which is preferably water and which may be heated if desired, is pumped into the pipe 30 and enters the bushing 31.

5 The cleaning fluid exerts a downward pressure on the cap 23 against the tension of the spring 34, whereby said cap is displaced downwardly. The ports 36 are located so that the cap may move downwardly a short 10 distance before said ports are uncovered. When the cap is moved downwardly the springs 24 and 26 will not be compressed to any extent and the plungers 21 will thus swing the head 16, whereby the nozzles 17 15 will be swung outwardly from their sockets into the well.

If one of the nozzles should encounter an obstruction the spring 24 of this plunger will yield, thus permitting the cap 23 to continue its downward movement and not interfering with the outward displacement of the other nozzles. This is a very important feature because if the obstruction to one of the nozzles prevented the outward displacement 25 of the other, the result obtained would not be as satisfactory. After the cap 23 has been displaced downwardly sufficiently to uncover the ports 36, the nozzles will have been swung to their outward limit and the cleaning fluid will pass into the collar 28 and down through the housing 10 to the nozzles. The cleaning fluid will thus be discharged in jets from the nozzles against the sides of the well proper, whereby the latter will be 30 cleansed. By rotating the pipe 30, the entire side walls of the pockets will be treated.

When the pressure of the cleaning fluid is cut off the spring 34 will immediately pull the cap upwardly until the pin 32 reaches the 40 top of the slots 33. The springs 26 resting on the fingers 22 will carry the plungers 21 upwardly, whereby the nozzles will be swung into the pockets 18. The device will offer an unobstructed contour and may be 45 withdrawn from the well. While I have shown four nozzles, it is to be understood that the number may be varied.

Various changes in the size and construction of the parts as well as modifications, 50 may be made without departing from the spirit of the invention.

What I claim, is:

1. In a well cleaning device, a housing having a plurality of openings, a nozzle 55 mounted within each opening of the housing and arranged to be swung outwardly from the opening of the housing, and means for simultaneously swinging said nozzles from

the housing, each nozzle being arranged to yield inwardly independently of the other 60 nozzles and the swinging means.

2. In a well cleaning device, a housing having a plurality of openings, a nozzle mounted in each opening and adapted to swing outwardly therefrom, fluid pressure 65 operated means for swinging the nozzles, and resilient means for independently sustaining each nozzle, whereby each nozzle may be depressed inwardly independently 70 of the other nozzle.

3. In a well cleaning device, a housing having a plurality of openings, pivoted nozzles mounted in the openings, a tubular fluid supply member, a valve normally obstructing the passage of fluid to the nozzles, 75 connections between the valve and the nozzles, said valve operating said connections to swing the nozzles outwardly, and resilient elements mounted on said connections, whereby each nozzle may be independently swung inwardly after having been 80 swung outwardly.

4. In a well cleaning device, a housing having a plurality of openings, a plurality of nozzles mounted in the openings and pivoted in the housing, a tubular fluid supply member projecting into the housing, a valve 85 slidably mounted on the member and normally obstructing the passage of fluid to the housing therefrom, means for sustaining the valve in its normal position, plungers connected with the nozzles and the valve, sustaining springs mounted on the plungers, and compression springs also mounted on the plungers, the valve having engagement 90 with the plungers relatively between the sustaining and compression springs.

5. In a well washing device, an elongated housing having a plurality of openings in its lower portion, a transverse support having sockets above the openings of the housing, nozzles having ball heads mounted in the sockets of said support, a tubular member in the upper end of the housing, a sliding cap mounted on the member, a coiled spring 100 supporting said cap, projections extending from the cap, plungers passing through said projections and having their lower ends connected to the heads of the nozzles, coiled 105 springs confined on the plungers between the projections and the nozzles, and sustaining coiled springs mounted on the plungers between the projections and the upper ends thereof.

In testimony whereof I affix my signature. 110
FRANK E. CROTTA.
